UNITED STATES PATENT OFFICE

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

RAIL GUIDE AND CLAMPING SURFACE FOR SHAPERS

Application filed June 24, 1927. Serial No. 201,180.

In shapers it is part of the usual construction to support the work table on a cross head movable transversely of the machine on ways provided on a cross-rail arranged at the forward face of the machine. The cross-rail in turn is adjustable vertically along ways on the forward face of the machine. These elements constitute means for the two major adjustments of the work table which may have associated therewith, when desired, various other means, such as tilting fixtures, for placing the work in the exact desired relation with respect to the cutting tool mounted on the ram designed to reciprocate in working relation with respect thereto.

This invention is particularly concerned with the arrangement of the vertical guideways and supporting surfaces for the cross-rail; the objects of the specific arrangement being directed to a location of the guides and bearing surfaces relative to the adjacent frame parts and to each other such that the machining thereof may be more easily and accurately accomplished, and at the same time result in a more rigid supporting means for the cross-rail and work table than has heretofore been accomplished.

A common construction, among the cross-rail supporting means, has been to provide two spaced vertical ways with the forward faces and respective outer edges thereof being planed surfaces whereby the forward faces may be utilized as cross-rail supporting surface and the outer edges in combination with angle portions on the cross-rail serving as guideways against transverse movements, the clamping being accomplished by the application of gibs to the rear face of the angle portions which gibs are adapted to engage the rear face of the guideways. Such constructions were found to have certain disadvantages as e. g. the rail guideways were too widely separated and the clamping of the rail with the rear gibs would not prevent and might even cause the cross-rail to bow or deflect from its normal shape.

As a remedy for such defects, supporting means have been provided wherein the clamping is accomplished by forming slotted openings through the supporting brackets de-

signed to accommodate bolts inserted into the cross-rail whereby the latter is clamped by a direct metal to metal contact with its ways. It was also found very advantageous, in combination with such means, to provide the inner edges of the ways with planed guideway surfaces; thus bringing the guideways closer together.

In the interests of providing a full and rigid support for the shaper ram in its forward positions, it has been found practical to project the ram guideways forwardly so that they extend at least as far as the forward face of the vertical rail bearings or what is even more common and desirable overhang a substantial amount. Such projecting portions, however, interfere with the planing of the vertical bearing surfaces for the cross-rail in the manufacture of the machine frame.

This invention has for its object a modification of (and additional improvements over) the direct clamping means and slotted ways, noted above, whereby the bearing surfaces may be more easily and cheaply machined without in any degree sacrificing any of the advantages derived from the preceding structure, but rather adding further to the rigidity of such improved supporting means. In prior constructions, wherein the cross-rails were held by the aforementioned angle portions and gibs (even when the ram ways did not project beyond the vertical forward bearing surfaces) the vertical guideways were necessarily either very widely spaced or, projected back underneath the ram ways thus, in the latter case, making the machining thereof a comparatively expensive operation.

The present invention includes, among its objects, an arrangement whereby the cross-rail guideways are located between the ram guideways; thus resulting in a more firmly supported cross-rail free from deflections and at the same time permitting the ready machining thereof without interference from the ram ways. Likewise the plane supporting surfaces are so positioned as to be clear of the ram guideways.

The complete and relative arrangement of

all the vertical surfaces for the cross-rails permits the entire machining thereof to be performed by conveniently assembling a number of the main supporting housings or frames in a straight line whereby they may be simultaneously operated upon by a large planing machine reducing to a great extent the production cost thereof and resulting in a more accurately machined product.

10 Other objects and advantages will be in part indicated in the following description and in part rendered apparent therefrom in connection with the annexed drawings.

15 To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

20 Fig. 1 is a view in elevation showing portions of a shaper machine. Fig. 2 is a front elevational view showing the cross-rail and various means for the adjustment thereof along its ways. Fig. 3 is a plan view of the cross-rail shown attached to the supporting frame, which frame is shown in cross section 25 and Fig. 4 is a plan view of a portion of the frame showing the ram guideways and the vertical guideways and supports for the cross-rail.

30 The invention comprises certain improvements in shapers, such portions only thereof being shown as are necessary to a full disclosure of the invention.

35 The general features include a base 10 supporting a main frame or housing 11 having at the upper part thereof the horizontally arranged spaced ram guideways 12. The forward wall 13 of the frame is provided with various guideways and means for supporting thereon for vertical adjustment the cross-rail 14 which in turn carries the work-table 40 15 adapted also to be adjusted transversely along the cross-rail. The forward wall 13 has integral therewith the projecting brackets or flanges 16 which have the front and rear machined plane surfaces 17 and 18 respectively. These flanges constitute means 45 for supporting the cross-rail in its adjusted position therealong.

50 The forward wall 13 also has machined therein the opposed guideway surfaces 19 and 20 adapted to receive and support the projecting bearing portion or guide 21 rigid with the cross-rail. The cross-rail and table is provided with the usual shield 22 adapted to 55 reciprocate therewith and to provide a protection for the working parts mounted below.

60 The means for adjusting the cross-rail in its vertical positions constitute chiefly, a vertical screw shaft 24 fixed in the base 10 and 65 having mounted thereon the rotary nut 25,

which nut has integral therewith a bevel gear 26. The nut 25 is rotatably mounted in the boss 27 and carries the vertical thrust of the table by means of the thrust bearing 28 mounted between the gear 26 and the bearing portion 27. Rotation of the nut 25 is accomplished by means of shaft 24^a having the bevel pinion 26^a thereon meshing with bevel gear 26.

70 Any desired means for adjusting the table 15 transversely of the machine may be provided, such means in the present case consisting of the cross-guide 30 having the forward bearing surface 31 along which the cross-head 29 integral with the table 15 may be moved by means of the screw shaft 32 having splined thereon a bevel gear 33 fixed against axial movement in the cross-head the hub end of the gear bearing against the nut 34 fixed in the cross-rail. The bevel gear 33 may be manually rotated by means of the shaft 35 having thereon the bevel pinion 36^a engaging with the bevel gear 33. For the sake of convenience in showing other parts the above gears and fixed nut have been omitted in Fig. 2. Any suitable automatic means may be connected to the horizontal shaft 32 for rotation thereof to likewise move the cross-head along its guides.

75 Very rigid and positive clamping means are provided for securing the cross-rail in its vertically adjusted positions consisting of the vertical slots 36 in the brackets 16 through which the spring tension bolts 37 and 38 attach to the cross-rail. Also projecting through the slots are the clamping bolts 39 having threaded thereon at their inner end and within the cross-rail the nuts 40 and 40'. All of these bolts 37, 38 and 39 project 80 through a pair of plates 41 adapted to bear against the rear plane surfaces 18 of the brackets 16. Suitable adjusting and locking nuts are provided for each of the bolts engaging the plates 41.

85 The manually operated means for operating the clamping bolts comprise a horizontal shaft 42 mounted within the cross-rail and having suitable connections such as is disclosed more fully in a co-pending application Serial No. 2,133 filed January 13, 1925 having a rack 43 and a worm 43' thereon in operative engagement with the nuts 40 and 40' whereby manual rotation of the shaft 42 by means of a wrench applied to the squared end 44 thereof rotates nuts 40 and 40' to securely draw the cross-rail into engagement with the bearing surface 17.

90 The above described elements constitute means, in combination with the centrally positioned guideways 19 and 20, for positively and rigidly securing the cross-rail to the supporting frame. The provision of the slots in the brackets and the clamping bolts extending therethrough result in the cross-rail being drawn into engagement with the flat sur-

face 17 by a direct metal to metal contact and the guideways 19 and 20 in combination therewith being centrally positioned between the clamping surfaces serve to prevent any twisting or bowing of the cross-rail such as might be present where the guides for the cross-rail are positioned at the outer edges of the brackets 16 and the cross-rail clamped thereto by an indirect angle arm projecting around the outer edge of the bracket 16.

10 The primary features of this invention are most clearly illustrated in Fig. 4 wherein the location of the various bearing and guide surfaces relative to each other and to the ram guideways is shown in a plan view thereof.

Heretofore various of these surfaces have been located in such position as to render the machining thereof comparatively difficult 20 and more expensive than the arrangement disclosed herein. As shown, the guideways 19 and 20 are positioned relatively close to the center of the structure and between the ram guideways 12. Likewise the brackets 25 16 extend vertically and, in horizontal projection thereof, outside of the ram guideways 12. This arrangement permits a plurality of the frame castings to be assembled in a straight line whereby they may be string 30 planed without any interference with the ram guideways 12 thereby rendering the production thereof a much more simple operation and resulting in reduced manufacturing costs; also, since the relative reciprocatory 35 movement between the cutting tool and frame consists of long strokes, the resulting surfaces are more accurately machined than if the strokes were short and ended at substantially the extremities of the respective planed surfaces.

40 In addition to the above advantages achieved in the process of manufacturing the frame castings, the resulting frames also have certain definite features which provide 45 a more rigid support for the cross-rail mounted thereon. The guideways 19 and 20 are brought closer together and nearer the center and the entire arrangement provides a four-point support for the cross-rail with 50 the points of support separated by substantial distances along the cross-rail.

55 In machines of this type the bearing surfaces, such as surfaces 17, are usually separated by a distance constituting a large portion of the comparatively short cross-rail 17. If the guideways are positioned at, for example, the outer edges of the brackets 16, the distance between the guideways is comparatively large relative to the total length of 60 the cross-rail and permits oftentimes serious bowing or deflection of the cross-rail at its middle portion.

65 While in many machines, it may be desirable to project the ram ways 12 a substantial amount beyond the vertical support-

ing surfaces and guideways in order that the ram may have a rigid support even in its most forward positions, the construction may be, and often is, such that the ram ways extend only to a point where they lie in the vertical plane of the surfaces 17. In such cases, the ends of the guideways can be planed off in the same planing operation as the surfaces 17 and also the surfaces 17 may, if desired, extend further toward the vertical guideways. With the above arrangement, the machining of the shaper frames would be accomplished in substantially the same manner as in the first construction described above, the guideways 19 and 20 being positioned, as shown, between the guideways 12 whereby the planer tool may be reciprocated therealong without engaging the ram guideways and likewise the surfaces 17 and 18 would be fully exposed for their ready machining.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of United States:—

1. A frame for shapers combining horizontally extending ram ways; a forward vertical wall adapted to support a cross-rail; and guideways and supporting surfaces on said wall for said cross-rail, said ram ways extending forwardly beyond the vertical wall and said guideways and supporting surfaces being so positioned that the longitudinal projections thereof pass adjacent to but without intersecting the frame parts providing said ram ways.

2. A shaper combining a main housing having a forward wall; a pair of spaced horizontal ram guideways mounted above and projecting forwardly beyond said wall; a table supporting element; means on said wall for adjustably mounting said element thereon comprising vertically extending supporting brackets arranged entirely outside the vertical plane containing the outer longitudinal edges of the respective projections having thereon the ram guideways, said brackets having front plane bearing surfaces, and vertical guideways arranged between said brackets and between the vertical planes containing the inner longitudinal edges of said projections; a guide on said element adapted to

- project into said guideways; bearing surfaces on said element adapted to directly engage said vertical surfaces; and means for clamping said element to said surfaces.
5. A shaper frame combining a supporting wall; ram guideways extending at substantially right angles thereto and projecting outwardly beyond said wall; and means for supporting a work table element on said wall for adjustment at right angles to the plane of said ram ways comprising plane bearing and supporting surfaces positioned with their axes extending outside said ram ways and other guideways positioned between said ram guideways said surfaces and other guideways being so arranged as to permit the straight line movement therealong and beyond the frame projections providing the outer ends of said ram ways of a machining tool without engaging said projections.
6. A shaper combining a frame having a forward wall; horizontal ram guideways mounted thereabove and projecting forwardly beyond said wall; a cross-rail; and means on said wall for supporting said cross-rail for vertical adjustment thereon comprising a pair of spaced vertical brackets each having a forward plane surface thereon and a vertical slot extending therethrough; vertical guideways located between said brackets and ram ways said surfaces and guideways being so arranged as to permit the movement therealong and beyond said ram ways of a cutting tool for the complete machining thereof without interference from said ram ways; bearing surfaces on said cross-rail for engaging said vertical guideways and surfaces; and clamping bolts attached to said cross-rail and extending through said slots.
10. A shaper combining a frame having a forward wall; a pair of spaced horizontal ram guideways mounted thereabove, said frame providing projections for extending said ram guideways forward of said wall; a table supporting element; and means on said wall for adjustably mounting said element thereon comprising a vertical flange arranged outside the vertical plane of the outer longitudinal edge of the respective said projections, said flanges having vertical slots therein and forward and rear plane surfaces, and vertical guideways arranged between said flanges and the vertical planes of the inner longitudinal edges of said projections; bearing portions on said element adapted to directly engage said guideways and forward plane surfaces; and clamping bolts attached to said element and projecting through said slot.
15. A shaper frame combining a forward vertical wall; horizontal spaced ram guideways mounted above said wall; and means on said wall for supporting a work table carrier comprising a vertical guideway the bearing surfaces of which lie in planes passing between said ram guideways, and vertically extending clamping surfaces on said wall, the arrangement being such that the ram guideways extend outwardly beyond said surfaces on said wall but with the said surfaces so positioned as to permit the movement therealong and beyond the outwardly projecting supports for said ramways of a tool for completely machining said surfaces without contacting said projecting supports.
20. A shaper combining a main frame; spaced horizontally extending ramways mounted thereon; and means for adjustably supporting a cross rail on the forward face of said frame comprising a vertically extending guideway, a vertical bracket on either side of said guideway having front and rear clamping surfaces, said ramways being carried by supports projecting forwardly beyond said guideway and brackets with the guideway arranged so that the vertical projection thereof passes between said projecting supports and the vertical projection of the clamping surfaces outside of said projecting supports and means for clamping said rail to said surfaces.
25. A shaper frame combining a forward vertical wall; a pair of horizontal ram guideway arranged above said wall, the frame being provided with supports carrying said ram guideways outwardly beyond said wall; cross-rail bearing and clamping surfaces on said wall arranged outside the vertical planes of the outer longitudinal edges of said ram supports; and cross-rail guideways arranged between the vertical planes of the inner longitudinal edges of said supports.
30. A shaper combining a frame having a forward wall; a pair of spaced horizontal projections extending forwardly beyond said wall, said frame and projections providing spaced ram guideways; a table supporting element; means on said wall for adjustably mounting said element thereon comprising a vertical flange arranged outside the vertical plane of the outer longitudinal edge of each of said projections, said flanges having a vertical slot and plane bearing surfaces, and vertical guideways arranged between the vertical planes of the inner longitudinal edges of said supports; and clamping bolts attached to said elements and extending through said slots.
35. A shaper combining a frame, spaced horizontal ram guideways on said frame and extending forwardly on supports projecting from said frame; a cross rail; and means for supporting said cross rail on said frame comprising vertically extending clamping surfaces arranged to the outer side of the vertical planes containing the outer longitudinal edges respectively of said supports, means for clamping the cross rail thereto, and vertically extending guideway surfaces for said carrier comprising a vertical guideway the

rail so arranged that the longitudinal projections thereof pass between said supports, whereby a cutting tool may be passed along said surfaces and beyond said ram guideway supports without interference with the latter.

In witness whereof, I have hereunto subscribed my name.

WILLIAM F. ZIMMERMANN.
